UNITED STATES PATENT OFFICE

99,204

DESIGN FOR A BUCKLE

Daniel T. Manning, Rochester, N. Y., assignor to
Hickok Manufacturing Company, Inc., Rochester, N. Y., a corporation of New York

Application January 30, 1936, Serial No. 60,904

Term of patent 3½ years

To all whom it may concern:

Be it known that I, Daniel T. Manning, a citizen of the United States, residing at Rochester, in the county of Monroe and State of New York, have invented a new, original, and ornamental Design for a Buckle, of which the following is a specification, reference being had to the accompanying drawing, forming part thereof.

Fig. 1 is a front view of the buckle.
Fig. 2 is a perspective view of the buckle.
I claim:
The ornamental design for a buckle, as shown.

DANIEL T. MANNING.
